UNITED STATES PATENT OFFICE

WILLIAM S. PARKER, OF ROCKFORD, ILLINOIS, ASSIGNOR TO BURSON KNITTING COMPANY, OF ROCKFORD, ILLINOIS, A CORPORATION OF ILLINOIS

DESIGN FOR A KNITTED FABRIC

Application filed March 3, 1930. Serial No. 34,714. Term of patent 7 years.

To all whom it may concern:

Be it known that I, WILLIAM S. PARKER, a citizen of the United States, residing at Rockford, in the county of Winnebago and State of Illinois, have invented a new, original, and ornamental Design for Knitted Fabric, of which the following is a specification, reference being had to the accompanying drawing, forming part thereof.

In the drawing—

The figure is a face view of a knitted fabric, showing my new design, a repeat unit of which is contained between the dot and dash lines on the drawing.

I claim:

The ornamental design for a knitted fabric, substantially as shown and described.

WILLIAM S. PARKER.
